UNITED STATES PATENT OFFICE

2,525,904

TAB PULLING MACHINE

Harry H. Hyde, Chicago, Ill.

Application June 23, 1945, Serial No. 601,299

14 Claims. (Cl. 101—1)

1

This invention relates to pulling machines, and particularly to a pulling machine for removing tabs and the like from carriers such as printing plates.

One class of printing machinery utilizes a printing plate adapted to be inserted in the machine to print an address or other suitable material. Such plates may be stored in accordance with an index system or stacked in a pile to be fed to and run through the printing machine and impressions taken from the plate.

It is often desirable to print from only certain plates or certain predetermined classes of plates. One method is to remove from the pile in which the plates are stacked, only those from which impressions are not to be made, and feed the remainder to the machine. This, of course, necessitates disrupting the sequence of the plates. Another method is to so control the printing mechanism that all of the plates may be fed to the machine, but the printing mechanism is so controlled by the plates themselves that impressions will be taken only from those plates from which it is desired that impressions be made. In this method the printing plates may be retained in their regular order, and the labor of selecting and removing from the stack those plates which are not to be printed is eliminated.

Printing plates which themselves control the operation of the printing machine are well known in the art, and an efficient system of tab controls has been devised whereby suitable pockets are provided in the printing plate to receive tabs which actuate the printing mechanism. A number of pockets are provided, and the location of the tab determines the printing operation to be performed. The tabs are held in place in the printing plate pockets by locking mechanism such as a spring tongue which engages a portion of the plate to prevent withdrawal of the tab, it being necessary to disengage the spring tongue before the tab can be withdrawn.

Where the number of plates from which impressions are to be taken is small and their use infrequent, it is feasible to remove the tabs by hand when it is desired to discontinue the operation or to transfer the tab to another position on the plate. To facilitate the removal operation somewhat and avoid injury to the hands of an operator, manually operable clamps have been devised for removing the tabs. The disadvantages of such devices have resided in the fact that the tab-pulling operation has been slow and inefficient, and both tabs and plates

have suffered frequent damage therefrom, requiring repairs or replacement.

The present invention overcomes the disadvantages in the previous methods employed, and has for an object the provision of a machine incorporating mechanism for automatically releasing the locking device which holds the tab in the printing plate, and then withdraws the tab and deposits it in a receptacle, the operation being repeated as rapidly as printing plates are fed to the machine.

Another object is to provide in a tab pulling mechanism a reciprocating gripper for seizing and withdrawing a tab from a printing plate, wherein lost motion is provided between the drive means for the reciprocating mechanism and the gripper to periodically immobilize the gripper.

Another object is to provide a tab pulling machine including a work holder to receive the plate with the tab locked therein, a reciprocable gripper and puller for removing the tab, a rotary disk operatively connected to the gripper and puller for reciprocation thereof, and a trigger device also actuated by the disk for unlocking the tab from the plate to permit the removal thereof by the gripper and puller.

A further object is to provide a tab pulling machine having a tab gripper and puller, a work holder for receiving a tab-carrying plate or the like, an indicator, and means for adjusting the work holder to indicated positions with the tab in operative position with respect to the gripper and puller.

Other objects and advantages of the invention will become clear from the following detailed description when read in conjunction with the accompanying drawings, wherein

Figure 1 is an end elevation of an apparatus embodying the features of the present invention, showing the movable work holder and guide, and the indicator for adjusting the work holder to the desired position.

Figure 2 is a plan view illustrating the apparatus of the present invention with the reciprocable operating mechanism in one of its operating positions.

Figure 3 is a partial plan view showing the reciprocable operating mechanism in another of its positions.

Figure 4 is a side elevation of the entire device with a portion of the combination support and housing cut away to indicate the driving connection between the motor and the reciprocable

mechanism, and with a printing plate in position to be inserted in the work holder.

Figure 5 is a section on the line 5—5 of Figure 4.

Figure 6 shows the tripping element or tab carried by the printing plate.

Figure 7 is a sectional view of a printing plate with a control tab carried thereby, and

Figure 8 is an enlarged detail, partly in section, of a portion of the tab pulling mechanism, showing the trigger and gripper jaws in position for releasing and withdrawing the tab from the printing plate.

Referring to the drawings, the numeral 1 designates a combination support and housing comprising a rectangular box having side walls 2 and 3, end walls 4 and 5, a base 6 and a cover member 7. End wall 4 projects upwardly above the cover 7 and has adjacent its upper end a bracket 8 which serves to seat the upper ends of a pair of spaced posts 9, the lower ends of which are anchored to the base 6. Cover 7 has a cut-out portion to accommodate the posts 9, and a carrier 11 is provided having openings to receive the posts for vertical sliding movement thereon.

Carrier 11 comprises a pair of blocks 12 and 13 having affixed therebetween the upper ends of a pair of laterally spaced, vertically extending guides 14 which project through an opening 15 in end wall 4 and are laterally flared in the manner indicated in Figures 1 and 2. The lower ends of guides 14 are secured to a second carrier 16 (see Figure 5) which is similar in structure to carrier 11 and has openings for the sliding reception of posts 9. Likewise affixed to carrier 16 is a platform 17 which projects outwardly from end wall 4 at right angles thereto, and, with guides 14, assists in correctly positioning a printing device or plate 18 with respect to the tab gripping and pulling mechanism, as will hereinafter appear. Also attached to the upper carrier 11 by bolts 19 is a member 20 having a laterally extending pointer 21 for movement over a numbered indicator 22 on the end wall 4.

Movement of the pointer 21 over the indicator to the various positions marked thereon is accomplished by the machine operator grasping the guide 14 and sliding it vertically on the posts 9. The guide is held in the selected position by a detent mechanism including a vertically extending strap 23, pivoted medially of its ends upon a bolt 24 carried by end wall 4. The upper end of strap 23 is provided with a bolt 25 extending through end wall 4 and laterally movable in a slot 26 therein (see Figure 5). Bolt 25 is provided with a handle 27 for laterally swinging the strap 23 about its pivot within the limits provided by slot 26. At the lower end of strap 23 is a narrowed portion 28 extending into an opening in a detent 29 suitably secured to the upper surface of cover 7 for limiting sliding movement thereover. Detent 29 is receivable in any of a plurality of notches 30 in a vertically extending latch member 31 secured at its upper and lower ends to carriers 11 and 16 by bolts 32 and 33, respectively. Detent 29 is biased in the direction of latch member 31 for reception in one of the notches 30 thereof by a spring 34 anchored to posts 35 and 36, provided on strap 23 and end wall 4 respectively (see Figures 4 and 5). By manipulation of handle 27 the detent 29 may be released from latching position with respect to member 31 so that the guides 14 may be moved upon the posts 9.

The operating mechanism of the apparatus of the present invention includes a conventional electric motor 37 supplied with energy through a plug and socket connection indicated at 38, and controlled from a switch 39 secured to the end wall 4. Motor 37 drives a vertically extending shaft 39a, preferably at a rate of approximately ninety revolutions per minute, although, if desired, suitable change-speed mechanism may be provided. The upper end of drive shaft 39a extends through the cover 7 and has mounted thereupon a rotary disk 40 having a cam surface 41, which functions in a manner hereinafter to be described.

Secured to the disk 40 for rotation therewith is a pivot bolt 42 having rotatively connected therewith a longitudinally extending link 43, the other end of which is similarly mounted upon a pin 44. Pin 44 is affixed to a reciprocating member 45 slidable upon a track indicated at 46 comprising laterally spaced rails 47 bolted to the cover 7. A groove 48 is provided in the outer side of each rail 47 to serve as guides for bolts 49 carried by member 45, and prevent dislocation of the latter. A longitudinally extending gripping member 50 is slidably mounted between the rails 47 and is movable relative to member 45. At this point it should be clear that operation of the motor 37 and rotation of disk 40 carrying the pivot bolt 42 results in reciprocation of member 45 at a rate dictated by the speed of operation of the motor.

Gripper member 50 includes a main body 51 having a jaw portion 52, and a relatively movable arm 53 having a mating jaw portion 54. Arm 53 is pivotally mounted upon the main body 51 by a bolt 55, and a spring 56 urges arm 53 in a direction away from the main body 51 to hold the jaws 52 and 54 normally out of gripping relation. Periodic overcoming of the bias of spring 56 to close the jaws of gripper 50 is accomplished by a mechanism including a link 57 pivoted upon a bolt 58 seated in the main body 51 of gripper 50. Secured to one end of link 57 by a bolt 59 is a roller 60 (see Figure 5) arranged to engage the outer surface of arm 53. The other end of link 57 is connected by a pivot bolt 61 to a link 62, the other end of which is pivoted upon a pin 63 seated in a reciprocable member 64 having bolts 65 slidably received in the grooves 48 in rails 47, and independently slidable with respect to gripper 50 and member 45.

Connection is made between reciprocable members 64 and 45 by a link 66 having one end mounted upon the pin 44 and provided at its other end with a hook 67 engageable with pin 63 on member 64. Pivotal movement of link 66 about pin 44 is limited by a pin 68 seated in reciprocating member 45, and received in a slot 69 in link 66. Hook link 66 is biased to engaged position with respect to the pin 63 by a spring 70 anchored to the link and to the member 45. At this point it should be understood that upon rotation of cam disc 40 from the position shown in Figure 2 the reciprocable member 45 is retracted and moves away from member 64 until hook 67 of link 66 engages pin 63, whereupon member 64 is likewise retracted. Retraction of member 64 swings link 57 about its pivot and closes the jaws 52 and 54.

Referring now particularly to Figures 4, 6 and 7, it may be noted that printing plate 18 is provided with a number of keeper slots or pockets 71, adapted to receive a control element or tab 72 in the manner indicated in Figure 4 and in

cross-section in Figure 7. Tab 72 comprises a head 73, preferably of a distinctive color or bearing other identification to indicate the operation to be actuated when the printing plate carrying the tab is fed to a printing machine. Tab 72 also includes a stem 74 and a spring tongue 75 which is bent outwardly upon insertion of the tab in one of the pockets 71, due to its curvature, and engages the wall 76 thereof, as shown in Figure 7. The tab cannot now be removed unless pressure is placed upon the tongue 75 to bring it back into alignment with the body of the tab, without damaging or destroying the tab.

In Figure 4 a printing plate 18 carrying a tab 72 is shown in position for insertion in the tab pulling machine, the position of the tab corresponding to the selected position shown on the indicator in Figure 1. In Figure 2 the printing plate is fully inserted to operative position for withdrawal of the tab 72 with the gripper in its farthest advanced position, and with the tab between the jaws 52 and 54 thereof.

In Figure 2, member 45 has reached its extension limit. In this position member 45 has abutted member 64 and pushed it forward into engagement with a pin 77 projecting upwardly from gripper 50, the forward edge of member 64 being notched at 78 to accommodate the pin. Contact of member 64 with the pin has advanced gripper 50 to the end of its stroke. The resultant rocking of link 57 in a clockwise direction has relieved the pressure of roller 60 on arm 53 to permit spring 56 to move jaw portion 54 away from jaw 52. In this position the head 73 of tab 72 is received between the gripper jaws and the jaws are now ready to close for withdrawal of the tab upon the return stroke of the gripper. To remove the tab 72 it is now necessary to disengage the spring tongue 75 from the wall 76 of slot 71 and return it to alignment with the main body of the tab, as indicated in Figure 8. This is accomplished by mechanism now to be described.

A lever 79 is pivotally mounted medially of its ends upon a pin 80 seated in cover 7 for rocking movement about a vertical axis, and is provided adjacent one end with a cam follower in the form of a roller 81 (see Figure 4) urged into engagement with the periphery of disk 40 by a spring 82 anchored to the end of the lever 79 and to the cover 7. The other end of the lever is provided with a post 83 having an opening therein threaded to receive a screw 84 adjustable therein, and arranged to engage a trigger device indicated generally at 85, and comprising a block 86 pivoted medially of its ends upon a bolt 87 seated in cover 7. One end of block 86 overlaps and engages one side of gripper 50 at the forward end thereof, and is resiliently held thereagainst by a compression spring 88 anchored at one end to an angle bracket 89, bolted to cover 7, and engaging block 86 at a location rearwardly removed from its pivot 87. Block 86 has secured thereto one end of a leaf spring 90, the other end of which parallels a narrowed portion 91 of the block to provide for oscillatory movement of the free end of the spring. A triangularly shaped hammer 92 is pivotally secured by a bolt 92a to a flange 92b on block 86. Hammer 92 engages the free end of spring 90, and oscillatory movement of the latter is adjustably limited in one direction by a screw 93 extending through the narrowed portion 91, the spring being depressed by the turning of the hammer upon its pivot.

As pointed out hereinbefore, the periphery of disk 40 engages the cam follower 81 carried by lever 79. In Figure 2 it will be observed that with gripper 50 in its farthest advanced position and with the tab 72 received between the jaws 52 and 54, the cam follower 81 has ridden upon cam surface 41 of the disk, rocking lever 79 about its pivot 80. The forward end of the lever has swung laterally and screw 84 has engaged the narrow portion 91 of trigger block 86, as indicated in Figure 2, and in detail in Figure 8. In Figure 8 it will be seen that hammer 92 has engaged spring tongue 75 and pressed it into alignment with the body of the tab 72 so that the tab can be withdrawn from its seat in printing plate 18, the hammer 92 being held in its deflected position until cam follower 81 has left cam surface 41 of the disk.

Rotation of the disk from the position shown in Figure 2 starts the reciprocable member 45 on its return stroke. This takes up the lost motion in the connecting linkage between member 45 and gripper 50 and brings hook 67 into engagement with pin 63 carried by member 64. Link 57 is rocked counter-clockwise to close the jaws 52 and 54 upon the head of tab 72, starting gripper 50 upon its return stroke. The tab is retained in the jaws of the gripper until the limit of the return stroke is reached, as shown in Figure 3, and another advance stroke initiated. Upon member 45 again overtaking and abutting member 64, link 57 is rocked clockwise and jaws 52 and 54 separate, releasing tab 72, which drops through an opening 94 in the cover 7 to a receptacle in the form of a removable drawer 95 therebelow, shown in section in Figure 5. Drawer 95 is provided with a handle 96 for removal and emptying thereof when filled. When a tab is encountered which has been damaged or improperly seated in the carrier and resists normal removal, the hook link 66, upon encountering pin 63, swings laterally against the bias of the spring 70 away from the pin within the limits permitted by the slot 69 and rolls upon the curved edge of the hook portion 67, returning to hooking position upon the return stroke of the link, without involving stoppage of the machine. The plate with the faulty tab is then removed and a new plate fed to the machine without interrupting the continuous operation thereof. The pivotal mounting of the hammer 92 permits it to roll upon the tab upon withdrawal thereof or upon the carrier if it is withdrawn before the trigger is retracted. Rocking of the hammer is resiliently inhibited by spring 90 pressing against the base thereof. Likewise, if a plate is inserted in the machine when the parts are in the position indicated in Figure 2, that is, with hammer 92 advanced as in Figure 8, the hammer rocks upon its pivot against the bias of the spring and does not interfere with the passage of the plate.

The function of the lost motion between member 45 and gripper 50 will become clear from the following: In Figure 2 the point of pivotal connection 42 is beginning to move in the direction of the arrow. At first, its longitudinal movement is slow due to the fact it is traveling in an arc and moves laterally as well as longitudinally. As soon as its predominant movement becomes longitudinal the speed of movement of the hook link 66 increases rather suddenly, the hook engages pin 63 and jaws 52 and 54 clamp upon and pull the tab 72. Upon the return stroke the suddenness with which member 45 engages mem-

ber 64 quickly opens the gripper jaws and jars the tab loose.

The operating mechanism of the tab pulling machine is protected by a canopy 97 secured to the cover 7 by bolts 98 and spaced therefrom by sleeves 99. The canopy is provided with vertically extending portion 100 at its forward end, secured to bracket 8.

Printing plates 108 may be fed to the machine rapidly and easily in synchronism with the cycle of operation thereof. Further, the removal of the spring-held tab from the printing plate or carrier is accomplished efficiently and without the damage to printing plates and tabs incident to the crude manually operable devices heretofore employed.

It should be understood, of course, that having described my invention in its preferred embodiment, various modifications may be made therein without departing from the spirit of the invention. Therefore, it is desired that my invention be limited only by the scope of the appended claims.

What is claimed is:

1. A machine for pulling tabs and the like from a carrier, comprising a support, a work holder on the support arranged to receive and position the tab carrier, means serving as a track on the support, a member slidable on the track, drive means on the support including a driven disk, a link pivotally connecting said member to the disk at a location removed from its axis to reciprocate the member, a gripper slidable on the track, means connecting the member to the gripper for reciprocation thereof, said connecting means including lost motion means for momentarily immobilizing the gripper at each end of its stroke, opposed jaws on the gripper arranged to receive the tab therebetween, means biasing the jaws to open position, and means associated with said lost motion connecting means for closing the jaws.

2. A machine for pulling tabs and the like from a carrier, comprising a support, a work holder on the support arranged to receive and position the tab carrier, a reciprocable member on the support, drive means on the support for reciprocating the reciprocable member, a tab gripper, means connecting the member to the gripper for reciprocation of the latter therewith from a retracted position to an advanced position in operative relation with a tab to be pulled, opposed jaws carried by the gripper for engaging the tab, means biasing the jaws to open position, means connecting the member and the gripper including lost motion means permitting predetermined movement of the reciprocable member in each direction prior to movement of the gripper, and means associated with the said lost motion means for opening and closing said jaws.

3. A machine for pulling a locked tab or the like from a carrier to which it is releasably locked, comprising a support, a work holder on the support arranged to receive and position the carrier and tab, a reciprocating gripping mechanism including relatively movable jaws, drive means for reciprocating the gripping mechanism, said drive means including a rotary disk, means for closing and opening the jaws during reciprocation thereof to withdraw and release the tab, means for unlocking the tab to permit withdrawal thereof, and means on the disk operable periodically during rotation thereof to actuate the unlocking means.

4. A machine for pulling a locked tab or the

like from a carrier to which it is releasably locked, comprising a support, a work holder on the support arranged to receive and position the carrier and tab, a reciprocating gripping mechanism including relatively movable jaws, drive means for reciprocating the gripping mechanism, said drive means including a rotary disc, means for closing and opening the jaws during reciprocation thereof to withdraw and release the tab, means for unlocking the tab to permit withdrawal thereof, and a cam surface on the disk operable during rotation thereof to periodically actuate the unlocking means.

5. A machine for pulling a locked tab or the like from a carrier to which it is releasably locked, comprising a support, a work holder arranged to receive and position the carrier and tab, a reciprocating mechanism including means serving as a clamp, drive means for the reciprocating mechanism, means operated by the drive means for actuating the clamping means to remove the tab, means independent of the clamping means for unlocking the tab to permit removal thereof, and means operated by the drive means for actuating the unlocking means.

6. A machine for pulling a locked tab or the like from a carrier to which it is releasably locked, comprising a support, a work holder arranged to receive and position the carrier and tab, a reciprocating mechanism including means serving as a clamp, drive means for the reciprocating mechanism, means operated by the drive means for actuating the clamping means to remove the tab, means for unlocking the tab to permit removal thereof, means operated by the drive means for actuating the unlocking means, and a lost motion connection between the reciprocating mechanism and the clamping means, whereby the clamping means is temporarily immobilized during operation of the unlocking means.

7. A machine for pulling a locked tab or the like from a carrier to which it is releasably locked, comprising a support, a work holder arranged to receive and position the carrier and tab, a reciprocating mechanism including pulling means, drive means for the reciprocating mechanism, means for actuating the pulling means during reciprocation thereof to remove the tab, unlocking means including a trigger device operable upon actuation of the pulling means to remove the tab and engageable with the tab lock for disengaging the latter from locking relation with the carrier, and means for actuating the trigger device.

8. A machine for pulling a locked tab or the like from a carrier to which it is releasably locked, comprising a support, a work holder arranged to receive and position the carrier and tab, a reciprocating mechanism including pulling means, drive means for the reciprocating mechanism including a rotatable disk, means for actuating the pulling means to remove the tab, unlocking means including a trigger device engageable with the tab lock for disengaging the latter from locking relation with the carrier, operating means for the trigger, a cam surface on the disk, and a cam follower carried by the trigger operating means for effecting periodic actuation of the trigger.

9. A machine for pulling a tab or the like having a flexible tongue member cooperable with the carrier for holding the tab therein comprising a support, a work holder arranged to receive and position the carrier and tab, a reciprocating

mechanism including pulling means, drive means for the reciprocating mechanism, means operated by the drive means for actuating the pulling means during reciprocation thereof to remove the tab, a trigger device including a hammer operable upon actuation of the pulling means to remove the tab and engageable with the flexible tongue member for the tab for releasing the latter, and means operated by the drive means for actuating the trigger device.

10. A machine for pulling tabs and the like from a carrier comprising a support, a work holder on the support arranged to receive and position the tab carrier, means serving as a track on the support, a member slidable on the track, drive means on the support for reciprocating the member, a gripper slidable on the track for seizing the tab, and connecting means between the member and the gripper for reciprocating the latter to seize and withdraw the tab, said connecting means being yieldable upon failure of the gripper to dislodge the tab.

11. In an apparatus for pulling tabs or the like from a carrier, a reciprocable member, a gripper for seizing the tab, and connecting means between the reciprocable member and the gripper for reciprocating the latter to withdraw the tab, said connecting means being yieldable upon encountering resistance to withdrawal of the tab.

12. In an apparatus for pulling tabs or the like from a carrier, a reciprocable member, a gripper for withdrawing the tab including opposed jaws, connecting means between the reciprocable member and the gripper for reciprocating the latter, means associated with the gripper and operable during reciprocation thereof for closing and opening the jaws to respectively withdraw and release the tab, said connecting means being yieldable when abnormal resistance to withdrawal of the tab is encountered.

13. In an apparatus for pulling from a carrier a tab or the like having locking means cooperable

with the carrier for holding the tab therein, a reciprocable member, a gripper for seizing the tab, connecting means between the reciprocable member and the gripper for reciprocating the latter to withdraw the tab, and means operable during reciprocation of the member for unlocking said locking means to permit withdrawal of the tab, said connecting means being yieldable when abnormal resistance to withdrawal of the tab is encountered.

14. A machine for pulling tabs and the like from a carrier comprising a work holder arranged to receive and position the carrier and tab, a gripper reciprocable to and from an operating position with respect to the tab, said gripper having jaws for seizing the tab upon retraction thereof, a member movable in directions corresponding to the advancing and retracting strokes of the gripper, means for moving the movable member, said member being movable through the first part of its advancing and retracting strokes at one speed and through the second part of said strokes at a relatively higher speed, a connection between the movable member and the gripper for reciprocating the latter, means operable through the first part of the member's advancing and retracting strokes for maintaining said jaws respectively closed and open, and means operable in the second part of said strokes for respectively opening and closing said jaws.
